(57) CLAIM

The ornamental design for a container for ornamental accessories, as shown and described.

DESCRIPTION

FIG. 1 is a perspective view of a container for ornamental accessories showing my design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view thereof in a closed position; and,

FIG. 9 is a perspective view of the container in use in a partially open position. The articles shown in broken lines in FIG. 9 illustrate environment and form no part of the claimed design.
